DESIGN FOR A COAT OR SIMILAR ARTICLE

Max Levitt, New York, N. Y.

Application June 30, 1942, Serial No. 107,372

Term of patent 3½ years

To all whom it may concern:

Be it known that I, Max Levitt, a citizen of the United States of America, residing at New York, in the county of New York and State of New York, have invented a new, original, and ornamental Design for a Coat or Similar Article, of which the following is a specification, reference being had to the accompanying drawing, constituting a part hereof.

Fig. 1 is a front view in perspective of a coat, showing my new design.

Fig. 2 is a rear view in perspective of the coat shown in Fig. 1.

Fig. 3 is a top plan view of Fig. 2.

I claim:

The ornamental design for a coat or similar article, as shown.

MAX LEVITT.
